(57) **CLAIM**

The ornamental design for a fishing reel handle cap as shown and described.

DESCRIPTION

FIG. 1 is a top perspective view of the fishing reel handle cap showing the new design;

FIG. 2 is a bottom perspective view of the fishing reel handle cap of FIG. 1 showing the new design;

FIG. 3 is a front view of the fishing reel handle cap of FIG. 1 showing the new design;

FIG. 4 is a rear view of the fishing reel handle cap of FIG. 1 showing the new design;

FIG. 5 is a top plan view of the fishing reel handle cap of FIG. 1 showing the new design;

FIG. 6 is a bottom plan view of the fishing reel handle cap of FIG. 1 showing the new design;

FIG. 7 is a right side view of the fishing reel handle cap of FIG. 1 showing the new design;

FIG. 8 is a left side view of the fishing reel handle cap of FIG. 1 showing the new design;

FIG. 9 is a cross-sectional view of the fishing reel handle cap of FIG. 5 along line 9-9 showing the new design; and, FIG. 10 illustrates the fishing reel handle cap in an environmental use configuration with a fishing reel.

The dot-dash broken lines in FIG. 5 depict the cross-sectional view along 9-9 and form no part of the claimed design. The evenly spaced broken lines in FIGS. 1-4 and 6-9 depict portions of a fishing reel handle cap that form no part of the claimed design. The evenly spaced broken lines in FIG. 10 depict environment of a fishing reel handle cap that forms no part of the claimed design.

1 Claim, 10 Drawing Sheets
